HYDRAULIC JACK AND METHOD IN THE
MANUFACTURE THEREOF

Richard W. Werner, Milwaukee, Wis.

Application February 26, 1937, Serial No. 127,831

2 Claims. (Cl. 60—52)

My invention relates to improvements in hydraulic jacks and methods in the manufacture thereof.

The object of my invention is to provide an entirely new arrangement of conduits in the base of a hydraulic jack whereby to simplify and lower the cost of construction of such jacks and to safeguard against leakage of high pressure oil.

Another object of my invention is to provide novel construction of the base, reservoir and ram cylinder of a hydraulic jack whereby the ram cylinder is assembled with the base and reservoir walls in a less costly manner and in such relation to the various parts as to accomplish and provide a most satisfactory assembly and successfully "block off" certain ducts which are made necessary by my process of forming the useful conduits in my jack.

In the drawing:

Figure 1 is a vertical section taken upon the diameter of the ram cylinder and pump of my improved jack.

Figure 2 is a section on line 2—2 of Figure 1.

Figure 3 is a section on line 3—3 of Figure 1.

Like parts are designated by the same reference characters throughout the several views.

The main structural elements of my hydraulic jack include a base 10 and reservoir 11, which I prefer to form in one casting or one structural unit; a ram cylinder 12, a ram 13, a threaded extension 14 for the ram, a pump including a pump piston 15, an actuator 16 therefor, together with a handle socket 17 and a handle 18 to operate 30 pivotally about a pin 19 secured to the outside of the reservoir 11; and a bleed valve 20.

Special attention is directed to the conduits formed in the lower or base portion of the main casting 9 forming the principal structural element of my improved jack and to the manner and purpose of mounting my ram cylinder in the principal casting 9 whereby to block off certain of the conduits which I form in the intermediate stages of the manufacture and which are not necessary to the operation of my completed jack.

As shown most clearly in Fig. 2, I form a conduit 21 with a counterbore 22 and a threaded pocket 23 substantially radially of the ram cylinder 12 at the extreme lower portion of the base and extending from the exterior thereof into the lowermost portion of the ram cylinder. A needle valve 24 in threaded and packed relation to a plug 25 seats against a shoulder 26 between the conduit 21 and its counterbore whereby to optional- 50 ly close the conduit against a pressure of liquid

in the ram cylinder. I form a pump cylinder 28 for the pump piston 15 and provide a pump supply duct 29 extending from the cylinder 28 downwardly into the base into communication at 30 with the counterbore 22.

The base is formed to provide an annular wall 31 shouldered internally at 32 to receive the ram cylinder 12. Before the ram cylinder 12 is placed in position I bore a hole through the reservoir wall at 33 and through the annular wall at 33 10 and I extend therethrough tools with which to bore a short conduit 36 and a counterbore 37 therefor, and I bore a conduit 38 which extends from the pump cylinder 28 downwardly to a junction at 39 with the short conduit 36. It will be 15 noted that the conduits extending downwardly from the pump cylinder are divergent, one being directed into the bleed valve and the other into the short conduit 36. Ball checks at 40 and 41 control the conduits 38 and 29 respectively. 20

A liquid feed conduit 42 extends from the counterbore 22 to the reservoir at a point 43 at the base of the reservoir and at such a position radially of the ram cylinder that when my hydraulic jack is in a reclining position on its "right" side the point 43 in the reservoir will be submerged by liquid from the reservoir and when the reservoir and jack structure is in a vertical position, the point 43 is likewise at a low point in the reservoir. This is true because the reservoir 30 wall is tapered inwardly upwardly and the lower portion of my jack reservoir is of larger radius than the upper portion. 25

Having formed the conduit 36 and having placed the ball check 40 in the counterbore 37 35 thereof, I insert a gasket 44 upon the annular shoulder 32 machined in the base and I then place the ram cylinder 12 in the position shown in Fig. 1. The upper tubular portion 46 of the reservoir is threaded interiorly and a swage nut 47 is 40 tightly threaded inserted against the top margin 48 of the ram cylinder, thus forcing the lower edge of the ram cylinder into liquid-tight relation to the gasket 44.

This method or sequence, of boring the holes at 45 35 and at 33 whereby to provide access for the boring of the short conduit 36 is of extreme importance since it enables me to arrange the conduits in the base in the cheapest and easiest manner and the ram cylinder blocks off the hole at 50 33 effectively.

Since the gasket 44 has a depending lip as seen clearly in Fig. 1, this lip overhangs the exit of the counterbore 37 sufficiently to prevent displacement of the ball 40. 55

- 5 A groove at 53 in the upper margin of the ram cylinder forms a bypass for liquid when the ram cylinder reaches the extreme upper limit of its movement. Packing at 49 and packing nut 50 complete the liquid-tight relation of the ram 13 with its ram cylinder and base casting 9.
- 10 The hole 35 in the side wall of the reservoir 11 is closed by means of a filler plug 51.
- 15 10 From the above description it will be seen that I have provided a hydraulic jack in which the conduits are easily formable in the base casting despite the fact that the walls of the reservoir formed integrally therewith are of such dimensions as to offer difficulty in the formation of ducts in the base. It will also be seen that when the complete jack is assembled, the only points at which high pressure liquid may escape to the exterior of the jack, are 20 through the packing 49 and past the pump plunger 15, which is of course equipped with the usual cup leathers as illustrated at 53 and through packing at 53'. At all other points the leakage of high pressure liquid will result merely in the passage of the leaking material to the reservoir.
- 25

In operation my jack accomplishes its purpose as follows: a lifting motion upon the handle 18 results in a movement of the pump piston 15 upwardly and outwardly of the cylinder 28 thus drawing liquid through the conduit 42 into the counterbore 22 through the conduit 29 and ball check 41 into the pump cylinder. It is understood of course, that the bleed valve is smaller 30 in diameter than the counterbore to provide for passage of oil thereby.

35 Upon a downward movement of the handle 18 the piston 15 is thrust downwardly so as to close

the ball check 41 and to pass liquid under pressure through conduit 38, short conduit 36, counterbore 37, and ball check 40 into the base of the ram cylinder. The ram cylinder is thereby forced upwardly so as to accomplish a lifting operation, and when the ram is to be lowered the needle valve 20-24 is threadedly rotated out of liquid-tight relation to the shoulder 26 whereby to release fluid from the ram through conduit 21 through the counterbore 22 and the 10 feed conduit 42 to the reservoir.

I claim:

1. In a hydraulic jack having a base formed with an upstanding reservoir wall and a centrally positioned annular wall having an inwardly extending shoulder, aligned conduits extending through the wall of the reservoir and through the said annular wall above the line of said shoulder and extending downwardly into the base below said shoulder to provide a short 20 conduit in said base and a ram cylinder receivable within said annular wall whereby to abut said shoulder and block off the conduit through said annular wall, said base being provided with a pump mechanism in communication with said 25 short conduit whereby to provide a flow of liquid into the ram cylinder.

2. In a hydraulic jack a base bored to receive a ram cylinder and having an annular shouldered wall against which said cylinder 30 may abut, said base having aligned conduits formed therein and intersecting said annular wall at an incline whereby to perforate said wall above the shoulder on one side and below the shoulder on the other side, and a ram cylinder 35 abutting said shoulder and positioned to block off one portion of said conduit.

RICHARD W. WERNER.
